UNITED STATES PATENT OFFICE.

GEORGE S. EVANS, OF LENOIR CITY, TENNESSEE.

BRAKE-SHOE.

1,085,555.

Specification of Letters Patent.

Patented Jan. 27, 1914.

Application filed September 6, 1913. Serial No. 788,397.

To all whom it may concern:

Be it known that I, GEORGE S. EVANS, a citizen of the United States, residing at Lenoir City, in the county of Loudon and State of Tennessee, have invented new and useful Improvements in Brake-Shoes, of which the following is a specification.

This invention relates to improvements in brake shoes for railway trains and especially with reference to improvements in brake shoes of the composite type in which the body of the shoe is made of cast iron and is provided with a steel reinforcing back onto which the body is cast during the process of the manufacture of the shoe, and also in which the body of the shoe is provided with a suitable number of inserts, preferably of nickel-chrome chilled steel so that the shoe is provided with a braking surface made up of a combination of metals having different frictional efficiencies, producing a shoe of maximum wear and braking qualities and enabling the shoe to secure certain desired results such as dressing the tread and flange of the wheel at points not worn by the rail, and thus retaining to a marked extent the original contour of the rim of the wheel, the invention being adapted for use in the construction of steel back brake shoes designed for use upon steel or steel tired locomotive driving wheels and being also adapted for use in steel back brake shoes for use on passenger and freight railway cars; the object of the invention being to provide an improved brake shoe embodying a steel or other metallic backing and a cast body in which the backing is embedded, possessing the maximum of safety and allowing for the maximum wear of the brake shoe and which will otherwise meet the other requirements set forth in the specification covering this class of device adapted by the Master Car Builders' Association.

With the above and other objects in view the invention consists in the construction, combination and arrangement of devices hereinafter described and claimed.

In the accompanying drawings: Figure 1 is a rear plan of a composite brake shoe constructed in accordance with my invention and especially adapted for use upon a steel or steel tired locomotive driving wheel. Fig. 2 is a vertical transverse sectional view of the same on the plane indicated by the line *a—a* of Fig. 1. Fig. 3 is a similar

view on the plane indicated by the line *b—b* of Fig. 1. Fig. 4 is a longitudinal sectional view of the same on the plane indicated by the line *c—c* of Fig. 1. Fig. 5 is a similar view on the plane indicated by the line *d—d* of Fig. 1. Fig. 6 is a plan of a blank from which the back of my improved brake shoe is formed. Fig. 7 is a front plan or elevation of my improved shoe. Fig. 8 is a detail transverse sectional view of a modified construction of the back. Fig. 9 is a vertical transverse sectional view of a form of brake shoe constructed in accordance with my invention and especially adapted for use on a passenger or freight car wheel. Fig. 10 is a detail transverse sectional view of the back of said shoe. Fig. 11 is a plan of the back. Fig. 12 is a plan of the blank from which the said back is formed.

Referring first to the form of my invention shown in Figs. 1 to 8, inclusive, and in which the brake shoe is especially constructed for use upon a steel or steel tired locomotive driving wheel I provide in accordance with my invention a back 1 which is preferably made of plate steel, a body 2 which is preferably made of cast iron and which body is cast onto and around the perforated back so that the latter becomes embedded therein, and inserts 3 embedded in the body of the shoe and exposed at the braking surface thereof, these inserts being of any suitable number, arranged at suitable points and being preferably made of nickel-chrome chilled steel.

The back is made from a blank A, such as shown in Fig. 6 and comprising a pair of straight parallel spaced arms 4 and 5 and a connecting bar 6 which is arranged medially of the arms 4 and 5. The arm 4 is wider than the arm 5 and is formed at its outer side with dove-tailed recesses 7, the arm 5 being formed with similar recesses 8 on its inner side. In the ends of the arm 4 are dove-tailed recesses 9 and in the ends of the arm 5 are notches 10, formed by integral lugs 11 which are inturned from the said arm. The inner side of the arm 4 of the blank is formed with alternately arranged dovetailed projections 12 and recesses 13 and the outer side of the arm 5 is formed with corresponding dove-tailed recesses 14 and projections 15, the former adapted to receive the projections 12 of the arm 4 and the latter adapted to fit in the recesses 13 of 110

said arm 4 as more fully hereinafter described. The said arms 4 and 5 are also provided with suitable openings 16.

In constructing a back for one of my 5 brake shoes from one of the blanks hereinbefore described the arm 4 is bent anti-clockwise through an angle of 90° on the line $e-e$, the arm 5 is bent in the same direction through an angle of 90° on the line 10 $f-f$ and the cross or connecting bar 6 is bent through an angle of 90° on each of the lines $g-g$ in such manner as to bring the arms 4 and 5 side by side, in contact with each other and interlocked with dove-tail projections 12 engaging the recesses 14 and the projections 15 engaging the recesses 13 so that the said arms 4 and 5 are thus firmly and securely locked together. Such bending of the bar 6 causes the same to form 15 the attaching lug or eye 17 of the finished brake shoe. After the blank has been thus bent to interlock the arms 4 and 5 and form the attaching eye or lug, the blank is then pressed by means of suitable dies or forged 20 or otherwise formed into a finished back and curved lengthwise to conform to the required curvature of the body, to fit on the periphery of a wheel and is also curved transversely to conform to the flange portion 25 of the cast shoe and if desired, the blank may also be corrugated as at 18 in Fig. 8 for the purpose of strengthening the corrugating portions of the back. When the back has thus been formed the body portion 2 of the shoe is cast therein and in a suitable mold, so that the back becomes embedded in the rear side of the body, and portions of the body flow into and fill the openings 16 in the back and hence the back and 30 body are firmly united, and each strengthens the other. While casting the body of the shoe the inserts 3, of nickel-chrome chilled steel are cast and embedded therein.

Referring especially to the form of my 45 invention shown in Figs. 9, 10, and 11, in which the brake shoe is adapted for use on a passenger or freight car wheel the back 19 is formed from a blank B such as shown in detail in Fig. 12, the said blank comprising 50 a pair of arms 20 spaced apart and arranged parallel with each other, and an integral bar 21 which connects the centers of the said arms. The arms 20 are formed with triangular notches 22 at opposite sides of 55 the ends of the bar 21 so that the latter is caused to extend nearly halfway across the arms 20. The said arms are provided in their outer sides with dove-tailed recesses 23 and are provided at their opposing inner 60 sides with matching dove-tail projections 24 and recesses 25 so that when the bar 21 is

bent on the line $h-h$ to dispose its end portions parallel with each other and bent from the arms 20, at right angles thereto and on the lines $i-i$ the said dove-tailed projections 24 are caused to engage in the recesses 25 and thereby lock the inner edges of the arms 20 together as shown in Fig. 11. The bent bar 21 is thus caused to form the attaching eye or lug 26 of the brake shoe. 65 70

The body 27 of the brake shoe is made of cast iron and cast onto the back, so that the latter becomes embedded in the body, and the said body is cast with bosses 28 which project from its rear side and in which the angles or sides of the lug or eye 26, where the same is united to the body, so that the said bosses serve to greatly strengthen the said attaching eye or lug as will be understood. 75 80

While I have herein shown and described two forms of my invention I would have it understood that other changes may be made without departing from the spirit of my invention and within the scope of the appended claims. 85

Having thus described my invention, I claim:

1. A brake shoe back comprising a pair of arms having interengaging edges, and a connecting portion between said arms and forming an attaching eye or lug. 90

2. A brake shoe back comprising a pair of arms having opposing edges interlocked from end to end and a connecting portion 95 between said arms, spanning the interlocked edges thereof and forming an attaching eye or lug.

3. A brake shoe back comprising a pair of arms dove-tailed together and a bar connecting said arms and also forming an attaching eye or lug. 100

4. A brake shoe back comprising a pair of arms and a connecting portion between said arms, and forming an attaching eye or 105 lug, said arms having opposing edges and integral means in the common plane of and to lock said edges together.

5. A blank for forming a back for a brake shoe, said blank comprising a pair of spaced 110 arms having matching edges adapted to interlock when said arms are brought together and a bar integral with and connecting said arms and adapted to be bent to form an attaching eye or lug. 115

In testimony whereof I affix my signature in presence of two witnesses.

GEORGE S. EVANS.
